US00D802102S

(12) **United States Design Patent** (10) Patent No.: **US D802,102 S**
(45) Date of Patent: ** Nov. 7, 2017

(54) **HOSE FITTING**

(71) Applicant: **Rockler Companies, Inc.**, Medina, MN (US)

(72) Inventors: **Emily Anne Mursu**, Plymouth, MN (US); **Daniel Lloyd Wenning**, Minnetonka, MN (US)

(73) Assignee: **Rockler Companies Incorporated**, Medina, MN (US)

(**) Term: **15 Years**

(21) Appl. No.: **29/548,644**

(22) Filed: **Dec. 15, 2015**

(51) LOC (10) Cl. **23-01**

(52) U.S. Cl.

USPC **D23/259**; D32/31

(57) **CLAIM**

The ornamental design for a hose fitting, as shown and described.

DESCRIPTION

FIG. 1 is a perspective view of a hose fitting;

FIG. 2 is a front view of the hose fitting of FIG. 1;

FIG. 3 is a rear view of the hose fitting of FIG. 1;

FIG. 4 is a side view of the hose fitting of FIG. 1 (as taken from the left of FIG. 2);

FIG. 5 is a side view of the hose fitting of FIG. 1 (as taken from the right of FIG. 2);

FIG. 6 is a top view of the hose fitting of FIG. 1; and,

FIG. 7 is a bottom view of the hose fitting of FIG. 1.

The broken lines in the FIGS. are for illustrative purposes only and form no part of the claimed design.

1 Claim, 6 Drawing Sheets
